UNITED STATES PATENT OFFICE.

JAMES R. STEELE, OF OWEGO, NEW YORK.

RAIL ANCHOR.

Application filed February 16, 1926. Serial No. 83,513.

This invention relates to the class of rail-anchors, or anticreepers as they are also called, and the object is to provide an exceedingly simple and inexpensive, and at 5 the same time, especially effective and advantageous and easily applied device made to grip one side flange only of the rail. The features and advantages of the invention will become apparent from the following 10 description and from an inspection of the accompanying drawings; in which:

Fig. 1 is a side elevation of a portion of a rail resting upon a tie-plate spiked to a tie, showing the rail-anchor in place;

Fig. 2 is a plan view;

Fig. 3 is a transverse vertical section;

Fig. 4 is a side view of the rail-anchor in its normal condition before application to the rail;

Fig. 5 is a bottom view of the same; and Fig. 6 is an end view of the device.

The letter *a* designates a railroad rail, and *b*, *b'* the flanges of its base. The rail rests upon a familiar tie-plate *c*, which is 25 spiked at opposite sides of the rail to the tie, by spikes *d*, and *d'* passing through holes in the tie-plate. The term "tie-plate" is used in this specification in the customary sense, meaning a plate-like bearing 30 member of any of the known or suitable forms such as, for example, that illustrated, intervening between the rail and the wood or, possibly, composition tie.

The rail-anchor, in the simplest and most 35 advantageous form now known to me, consists of a substantially flat, narrow bar 2 of oil-treated spring steel, having integral lateral extensions or ears at its opposite ends, or remote portions, these ears being 40 re-bent under the bar to make jaws 3, 3^a formed approximately to fit over and under the outer portion of the flange. The vertical dimensions of the openings of the jaws are preferably such that the jaws are 45 sprung or spread open slightly in driving or forcing them onto the flange, but not beyond the elastic limit. In addition to, or in the absence of such tensional gripping capacity of the jaws themselves, an important 50 tensional grip is obtained by virtue of a straining of the body of the bar of the anchor, in application to the rail, as will be hereinafter described.

The bar 2 is of such length, and the jaws 55 3 are so spaced, that when the device is in position on the rail-flange, the backs 4

and lower members 5 of the jaws are in contact with, or adjacent to, the opposite, forward and rearward, edges of the tie-plate; furthermore said lower members 5 are preferably not lower than the tie-plate, so as to be accommodated between the tie and the rail, without injury to the tie. The tie-plate, not the tie, constitutes the abutment for the rail-anchor, and the invention, 60 by very simple means, makes it possible to utilize the tie-plate as a double abutment, against movement either forward or back of the rail. The double abutment relation need not, and indeed should not, be too close 65 however, as expansion and some slight play should be allowed for; hence the spacing between the jaws is slightly greater than the width of the plate.

In applying the rail-anchor to the rail, 75 the jaw 3 is first applied to or driven onto the outer rail-flange. It will be noted that the bar, in manufacture, is given a transverse bend in the vertical sense, the locus of the bend being preferably near the jaw 3, so that when this jaw is first applied the jaw 3^a is elevated out of line, somewhat above the edge of the rail-flange. In addition, or alternately, the bar was given a 80 twist about a longitudinal axis, relatively 85 rotating the jaws out of line. Consequen- 90 tly, to complete the application of the rail-anchor, it is necessary to bend the bar down and twist it against its resilient set, but not beyond its elastic limit, in order 95 that the jaw 3^a may be driven onto the flange. In this way, a very effective frictional and tensional grip of the anchor on the rail is obtained.

The shanks of the spikes *d* which fasten 100 the tie-plate to the tie at the outer side of the rail pass immediately at the outer side or edge of the bar 2, and consequently serve the further purpose of backing up the anchor to prevent it working laterally off the rail flange under vibration or other forces.

As many of these rail-anchors will be applied as are necessary to hold the creep of the rail without overloading the spikes. 105 Owing to the simple and inexpensive nature of the device, more of them can be used if desired than of rail-anchors now on the market, without greater, or as great, cost or more, or as much, labor in installation and maintenance. The cost of both manufacture and maintenance is low. Fur-

ther important advantages of this rail-anchor over ordinary types are that it is not liable to injury from dangling equipment or by derailment, that the ballast does not have to be dug out and that there is no problem of frozen ballast and of the anchors working loose by reason thereof, and that the form of the tie is immaterial. The tie is the abutment for almost all rail anchors that have been proposed, and is for all that are in actual use as far as I am aware; and, when the tie is of the "post" variety, it does not afford an advantageous abutment for such anchors. Furthermore, ties may be narrower than the tie-plates, so that the tie-plates project beyond the tops of the ties, in which event a satisfactory abutment is not afforded for ordinary rail-anchors; such a condition, however, being entirely suitable for this device.

What I claim as new is:

1. A rail-anchor constructed to be applied to one side flange of a rail so as to straddle a tie-plate in double abutment relation to such plate, substantially as set forth.

2. A rail-anchor constructed to be applied to one side flange of a rail in frictional and tensional engagement therewith, and to straddle a tie-plate in double abutment relation to such plate, substantially as set forth.

3. A rail-anchor constructed to be applied to one side flange of a rail in frictional and tensional engagement therewith, and to cooperate in abutment with the tie-plate between the rail and the tie, substantially as set forth.

4. A rail-anchor which is applied to one side flange of a rail, said rail-anchor having jaws spaced and adapted to grip said rail-flange at opposite sides of a tie-plate and to cooperate with said plate in double abutment, substantially as set forth.

5. A rail-anchor which is applied to one side flange of a rail, said rail-anchor comprising a one-piece spring member having jaws spaced and adapted to grip said rail-flange at opposite sides of a tie-plate and to cooperate with said plate in double abutment, substantially as set forth.

6. A rail-anchor which is applied to one side flange of a rail, said rail-anchor comprising a longitudinal bar member having jaws spaced and adapted to grip said rail-flange at opposite sides of a tie-plate constituting the abutment for the rail-anchor, the member being made so that the jaws are out of alinement before application involving a distortion in application producing a tensional grip on the rail flange, substantially as set forth.

7. A rail-anchor which is applied to one side flange of a rail, said rail-anchor comprising a longitudinal bar member having

bent jaws on its remote portions spaced and adapted to grip the rail flange at opposite sides of the tie-plate with which to co-operate as the abutment, said bar as made being distorted to compel a tensional grip on the rail flange, substantially as set forth.

8. A rail-anchor which is applied to one side flange of a rail, said rail-anchor comprising a longitudinal bar member having jaws spaced and adapted to grip the rail-flange at opposite sides of the tie-plate with which to cooperate as the abutment, said bar member as made being bent laterally in the vertical sense so that when one jaw is engaged with the rail-flange the member must be sprung against its resilience to engage the other jaw with the rail-flange, substantially as set forth.

9. A rail-anchor which is applied to one side flange of a rail, said rail-anchor comprising a longitudinal bar member having jaws spaced and adapted to grip the rail flange at opposite sides of the tie-plate with which to cooperate as the abutment, said bar member as made having a longitudinal twist rotating the jaws out of line, substantially as set forth.

10. A rail-anchor which is applied to one side flange of a rail, said rail-anchor comprising a longitudinal bar member having jaws spaced and adapted to grip the rail flange at opposite sides of the tie-plate with which to cooperate as the abutment, said bar member as made having both a longitudinal twist and a lateral bend in the vertical sense, substantially as set forth.

11. A rail-anchor which is applied to one side flange of a rail, said rail-anchor comprising a longitudinal resilient member adapted to overlie one side flange of a rail and having spaced integral portions re-bent under the bar so as to grip the rail-flange at opposite sides of the tie-plate, substantially as set forth.

12. The combination with a rail and a tie-plate spiked to a tie, of a device of the character described having spaced portions in gripping engagement with one side flange of a rail and in abutment relation to opposite edges of the tie-plate, substantially as set forth.

13. The combination with a rail, a tie-plate and a spike, of a device of the character described having spaced portions in gripping engagement with one side flange of a rail and in abutment relation to opposite edges of the tie-plate, and backed up at the side away from the rail by said spike.

14. The combination with a rail and a tie-plate, of a longitudinal distorted resilient bar member having spaced portions adapted to grip one side flange of the rail and to co-operate with the tie-plate as an abutment.
